(57) **CLAIM**

The ornamental design for a zipper pull, as shown and described.

DESCRIPTION

FIG. 1 is a front elevational view of the zipper pull of the present invention;

FIG. 2 is a rear elevational view of the zipper pull of FIG. 1; FIG. 3 is a left side elevational view of the zipper pull of FIG. 1; FIG. 4 is a right side elevational view of the zipper pull of FIG. 1;

FIG. 5 is a top view of the zipper pull of FIG. 1; FIG. 6 is a bottom view of the zipper pull of FIG. 1; FIG. 7 is a perspective view of the zipper pull of FIG. 1; and, FIG. 8 is another perspective view of the zipper pull of FIG. 1, showing the zipper pull on a mattress cover assembly. The broken line showing of mattress cover assemblies in FIG. 8 is included for the purpose of illustrating environment only and forms no part of the claimed design.
